Primary Examiner — Kevin K Rudzinski*Assistant Examiner* — Paul D Bohannon(74) *Attorney, Agent, or Firm* — Mark Malek; Widerman Malek, PL(57) **CLAIM**

The ornamental design for a swing, as shown and described.

DESCRIPTION

FIG. 1 is a front perspective view of a swing according to the present invention.

FIG. 2 is a side elevation view of the swing illustrated in FIG. 1.

FIG. 3 is another side elevation view of the swing illustrated in FIG. 1.

FIG. 4 is another side elevation view of the swing illustrated in FIG. 1.

FIG. 5 is another side elevation view of the swing illustrated in FIG. 1.

FIG. 6 is a top plan view of the swing illustrated in FIG. 1; and,

FIG. 7 is a bottom plan view of the swing illustrated in FIG. 1.

The broken lines showing strings, hooks, and a child are for the purpose of illustrating environmental structure and form no part of the claimed design.

1 Claim, 7 Drawing Sheets(56)
